UNITED STATES PATENT OFFICE.

HARVEY M. GERSMAN, OF CHICAGO, ILLINOIS.

PRODUCTION OF EXPANDED SHEET METAL.

Original application filed May 27, 1921, Serial No. 473,062. Divided and this application filed June 1, 1923. Serial No. 642,871.

To all whom it may concern:

Be it known that I, HARVEY M. GERSMAN, a citizen of the United States, residing at Chicago, in the county of Cook and State of Illinois, have invented a new and useful Improvement in the Production of Expanded Sheet Metal, of which the following is a specification.

This application is filed as a division of 10 my application, Serial No. 473,062 filed May 27, 1921, in so far as concerns the subject matter of claims cancelled from said application pursuant to the divisional requirement therein made.

15 This invention relates to the production of expanded sheet metal and its principal object is to provide a method of simple character for the production of expanded sheet metal having novel structural features 20 and novel and superior qualities, such expanded metal forming the subject of my co-pending application, Serial No. 642,870.

The manner of practicing the invention 25 will be apparent from the accompanying drawing, taken in connection with the description which follows.

In said drawing:

Figures 1 and 2, respectively, are plan and edge views of the blank in a form prescribed 30 by the present method.

Figure 3 is a detailed plan view of the expanded sheet metal produced from the blank of Figure 1.

Figures 4 and 5 are detailed sectional views in the planes 4-4 and 5-5 respectively, of Figure 3.

In the expanded metal the strands 11 and the webs or connecting portions 12 delimit 40 hexagonal cells or voids 13 and, as in the ordinary expanded metal lathing, the hexagonal form of the cells is such that they are arranged in parallel rows whose axes are normal to and bisect the parts 12 as will appear by the alternately arranged broken 45 lines A and B.

The blank from which the expanded metal is produced is provided with slits which aline in the direction of their length and are thereby arranged in rows disposed transversely of the sheet, the slits of one row being arranged in staggered or break-joint position relatively to the slits of adjacent rows; and the webs or junction portions of 50 the expanded metal are substantially provided by the material which lies between

the ends of the adjacent slits of each row and between the alining slits of the alternate rows.

By the present method the blank, which to start with is flat and provided with the 60 slits described, is formed with longitudinal corrugations, that is to say corrugations which are normal to the slits, and these are so arranged that the alternate longitudinal rows of junction portions are offset relatively to the mean plane of the sheet whereby the junction portions of rows B lie at one side of said mean plane and the junction portions of rows A lie at the opposite side of 65 said mean plane. The junction portions form the apices of the corrugations and are presented flat or substantially so whereby the portions of the metal which connect the junction portions of adjacent rows 70 extend athwart the mean plane of the 75 blank at a well defined angle to such junction portions.

The method preferably includes the formation of minor corrugations inverse and 80 parallel to the corrugations above described 85 (and which may be designated as "major corrugations") and within which the junction portions 12 lie, the minor corrugations being indicated at 14 in Figures 1 and 2; and where the minor corrugations are employed the slits are extended slightly at their 90 ends into the portions in which the minor corrugations are formed. By virtue of the minor corrugations the webs or junction portions 12 are transversely concave and ridges 15^a are formed in the parts which 95 extend transversely between the junction portions of adjacent rows, the said ridges extending longitudinally of the sheet and transversely of the parts in which they are formed and lying near the extremities of the slits.

The blank having, by virtue of the steps 100 of the present method, the form above described and shown in Figures 1 and 2, is expanded in the usual manner to produce the finished product shown in Figure 3. The location of the ends of the slits in the blank with reference to the longitudinal centers of 105 the webs as indicated by the lines C, that is to say the central axes of the webs at right angles to the axes of the rows A and B, in conjunction with the provision of the major corrugations determines the planes of the webs in the expanded sheet. In the ex- 110

expanded sheet the major corrugations are maintained and the junction portions of the alternate rows lie in relatively the same planes as in the blank. The best results are obtained by having the central portions of the webs of rows at the same side of the sheet in a common plane and for this purpose the ends of the slits in the blank terminate in coincidence with the longitudinal centers of the webs. However, results substantially better in degree than is possible with expanded lathing of the ordinary construction may be obtained, within the scope and contemplation of the invention, in various cases where the slits are so arranged that the webs or junction portions of the expanded sheet will lie at an angle to their mean planes, the value of the results increasing with the approach of the central portions of the junction portions to exact co-planar relation. While very good results may be obtained in cases where the webs or junction portions of the expanded metal are truly flat throughout their extent the best results are obtained where, as shown, the junction portions are substantially flat relatively to the mean plane of the sheet while yet being slightly concave in the transverse direction of the sheet, that is to say the direction at right angles to the rows A and B, and the strands are formed with ridges 15 extending transversely thereof and closely adjacent their lines of union with the junction portions. As the blank is expanded the strands are bent laterally away from the junction portions from which they extend and are deformed along the ridges 15 so as to provide the ridges 15 in the finished sheet. The ridges 15 increase in height from their mean to their extreme ends and, being produced by the deformation of the strands consequent to the expansion of the blank, prevent the development of stresses incident to such expansion which might otherwise result in the partial rupture of the strands along or substantially along their lines of union with the junction portions. It follows that by virtue of the minor corrugations 14 the slits may be made longer with resultant larger voids in the expanded metal than would otherwise be possible. In this way a greater degree of expansion with a consequent reduction in weight is secured while at the same time the strength of the expanded metal sheet is not impaired. In fact the ridges 15 serve as reinforcements for the strands and tend to increase the stiffness and pressure resisting quality of the sheet.

In the expanded sheet the strands extend in inclined or angular directions athwart the mean plane of the sheet and present the greatest effective area to resist the thrusts incident to the application of the plaster. This will be apparent when it

is considered that the planes of the strands substantially coincide with lines parallel to the axes of the rows A and B in the mean plane of the sheet. The depths of the major corrugations will be such as to insure good clinching and keying effects while at the same time all, or nearly all of the area of the webs and the strands is utilized to resist the thrusts incident to the application of the plaster, thereby avoiding cutting through the plaster and minimizing the loss and waste of plaster by seepage. If desired the major corrugations may be made sufficiently deep to serve as furring strips at either side of the sheet, a self furring quality being thereby provided.

Having fully described my invention, I claim:

1. The method of producing expanded sheet metal which consists in slitting the blank, the slits being arranged in parallel transverse rows with the slits of one row in break-joint position relatively to the slits of the adjacent rows, longitudinally corrugating the blank to offset the rows of junction portions alternately at opposite sides of the mean plane of the sheet and expanding the blank so slitted and corrugated.

2. The method of producing expanded sheet metal which consists in slitting the blank, the slits being arranged in parallel transverse rows with the slits of one row in break-joint position relatively to the slits of the adjacent rows, longitudinally corrugating the blank to offset the rows of junction portions alternately at opposite sides of the mean plane of the sheet and locating the ends of the slits relatively to the central axes of the junction portions so as to determine the planes of the junction portions in the expanded sheet and expanding the blank so slitted and corrugated.

3. The method of producing expanded sheet metal which consists in slitting the blank, the slits being arranged in parallel transverse rows with the slits of one row in break-joint position relatively to the slits of the adjacent rows, forming longitudinal major corrugations in the blank whereby the junction portions are offset relatively to the mean plane of the sheet in parallel longitudinal rows, forming minor corrugations in the blank inverse and parallel to the major corrugations and in which the slits extend slightly at their ends, and expanding the blank so slitted and corrugated.

4. The method of producing expanded sheet metal which consists in slitting the blank, the slits being arranged in parallel transverse rows with the slits of one row in break-joint position relatively to the slits of adjacent rows, longitudinally corrugating the blank whereby the parts which con-

nect the junction portions extend at an angle thereto and to the mean plane of the blank, and expanding the blank so slitted and corrugated whereby said parts are bent closely adjacent their lines of union with the junction portions at an angle to the direction in which they extend athwart the mean plane of the blank.

5. The method of producing expanded sheet metal which consists in slitting the blank, the slits being arranged in parallel transverse rows with the slits of one row in break-joint position relatively to the slits of adjacent rows, forming longitudinal

major corrugations in the blank whereby 15 the parts which connect the junction portions extend at an angle thereto and to the mean plane of the blank, forming minor corrugations in the blank inverse and parallel to the major corrugations and in which 20 the junction portions lie and into which the slits extend slightly at their ends, and expanding the blank so slitted and corrugated.

10 In testimony whereof I affix my signature.

HARVEY M. GERSMAN.
